COMBINATION HUMIDIFIER AND FILTER

Joseph G. Dicaire, Flint, Mich.

Application November 15, 1939, Serial No. 304,463

2 Claims. (Cl. 98—109)

This invention relates to a device for use in connection with hot air registers usually built in the wall of a room at or near the outlet of a hot air conductor or duct from a furnace.

5 One of the prime objects of the invention is to design an inexpensive and efficient structure to provide necessary and ample moisture in a room which is heated by a hot air furnace, and also provide means connected therewith for filtering dust and foreign matter from the hot air as it flows from the register.

Another object is to provide a simple, neat appearing attachment which can be easily or quickly mounted or detached to registers already installed, which can be readily filled with liquid for supplying moisture, which requires a minimum of space, and in which the air currents are deflected away from the wall as they rise from the register.

20 A further object is to provide a device including easily removable dust filters disposed in the path of the rising heat currents, which filters are easily removable and replaceable when necessary to remove for cleaning, repair, or replacement with new filters.

The above and other objects will appear as the specification progresses, reference being had to the accompanying drawing in which I have shown the preferred embodiment of my invention, and in which like reference numerals indicate like parts throughout the several views thereof.

In the drawing:

Fig. 1 is an enlarged front elevational view of my combination humidifier and air filter.

Fig. 2 is a top plan view thereof with the cover broken away to show the liquid tank.

Fig. 3 is an end elevational view, the broken lines showing the cover swung upwardly to give access to the tank.

Fig. 4 is an enlarged fragmentary edge view showing the manner of mounting the filter strips.

Fig. 5 is an enlarged perspective view of my improved combination humidifier and dust filter, showing it mounted in position on a conventional hot air register.

Referring now more particularly to the drawing in which I have shown the preferred embodiment of my invention, the numeral 8 indicates a wall in which a hot air register 9 is provided as usual, this register being secured to the wall by means of screws (not shown) or in any other approved manner. The device is preferably formed of sheet metal suitably finished to harmonize with the register and room furnishing and comprises

an elongated tank B formed to comprise front, back, and bottom panels 10, 11, and 12 respectively, to which the end members 13 are soldered or welded in the conventional manner, the back panel 11 projecting a predetermined distance 5 below the bottom of the tank as indicated at 14 and for a purpose to be presently described.

A perforated cover member 15 forms a closure for the open upper end of the tank and is secured thereto by means of hinges 16 so that the cover 10 may be swung upwardly as clearly shown in broken lines in Fig. 3 of the drawing to permit filling of the tank with water, or for cleaning, repairing, or any other purpose.

The front edges of the end members 13 are 15 angled as shown at 17 to enhance the appearance and clips 18 are punched in these end wall members in spaced relation, said clips being bent inwardly and thence upwardly to accommodate a short rod or wire section 19 to which one end of a strip of filter cloth 20 is secured, either by sewing or in any other approved manner. A similar rod is provided on the opposite end of this filter cloth 20, and when these rods are mounted in these clips, this strip spans the distance between the end walls of the device and is disposed directly in the path of the rising heat currents. There can be as many strips as desired, and these are preferably mounted at an angle with relation to the tank B so that the upwardly flowing air currents will pass therethrough, filtering out dust and other foreign matter carried thereby, said air currents heating the tank so that the liquid contained therein will be evaporated through the perforated cover and the air in the room properly humidified.

The mounting of the device in position on a register is very simple and easy. It is merely necessary to slightly loosen the screws (not shown) which secure the register 9 to the wall. 40 The depending lip 14 which depends from the tank is then inserted between the wall 8 and the inner edge of the register 9, so that the bottom of the tank rests on the upper edge of said register, after which the securing screws are 45 again tightened and the mounting is completed.

To fill the tank it is merely necessary to swing the cover 15 to gain access to the tank and the dust filters can be easily removed by lifting the rods 19 out of the clips 18 in the end members 50 so that the filter cloth can be removed, cleaned, and replaced as desired.

The dust filters 20 are preferably mounted at an angle as shown in Fig. 3 so that some of the air currents will be, in a measure, diverted in- 55

wardly to more uniformly heat the tank and also to provide for greater filtering efficiency.

From the foregoing description, it will be clearly obvious that I have perfected a very simple, 5 practical, attractive, and inexpensive combination humidifier and air filter for hot air registers and the like.

What I claim is:

1. A combination humidifier and filter comprising a sheet metal tank including end members depending below the bottom of the tank, a 10 lip on the back wall of the tank and adapted to be inserted between a wall and a hot air register for securing the tank in position, a perforated 15 cover hingedly mounted on said tank, spaced clips punched in the end members and projecting inwardly and upwardly to form supports, and a flexible filter member having pins on the ends

thereof for detachable engagement with said supports so as to secure said filter member in a horizontal and taut position.

2. A combination humidifier and filter comprising a tank including end members adapted 5 to snugly fit the side wall of a hot air register, a perforated cover hingedly connected to and forming a closure for the top of the tank, a lip on the back wall of the tank and adapted to be interposed between the wall and a hot air register, 10 triangular clips punched in the end members in spaced relation to the ends extending upwardly to form sharp supports, strips of filter cloth disposed and stretched between said end members and rods secured to said strips and adapted to 15 be detachably mounted on said supports.

JOSEPH G. DICAIRE.
